UNITED STATES PATENT OFFICE.

CHARLES A. LINDSTROM, OF CHICAGO, ILLINOIS.

DESIGN FOR A FIELD RING OR FRAME FOR ELECTRIC MOTORS.

SPECIFICATION forming part of Design No. 32,325, dated March 6, 1900.

Application filed December 1, 1899. Serial No. 738,927. Term of patent 14 years.

To all whom it may concern:

Be it known that I, CHARLES A. LINDSTROM, a citizen of the United States, residing at Chicago, in the county of Cook and State of Illinois, have invented and produced a new and original Design for the Field Ring or Frame of Electric Motors, of which the following is a specification, reference being had to the accompanying drawings, forming part thereof.

5 In the drawings, Figure 1 is an end view of a field ring or frame of an electric motor embodying my new design. Fig. 2 is an edge view of the ring, partly broken away to show the peculiar location of the field-poles.

10 The principal feature of my new design consists in a circular field-ring A, having its outer circumference convex in cross-section, provided with flat slightly-raised marginal surfaces b at its ends, said surfaces extending

15 inwardly, so as to constrict the internal diameter of the ring at the ends thereof and having four similar equidistant field-poles B, projecting radially inward from its inner circumference, angular in cross-section.

20 The inner ends of field-poles B are concaved and separated by intervals equaling one and one-quarter times the width of said poles, and their length corresponds to about one-fourth the diameter of the field-ring, and they are

25 located midway between the ends of the ring, as clearly shown in Fig. 2. The field-ring also has a slightly-raised flattened attaching-surface C, projecting from its outer periphery at

one side, and a suspending-lug D, projecting therefrom almost diametrically opposite the 35 surface C.

The end openings of the field-ring are of less diameter than that of the inner circumference of the field-ring proper, from which the four field-poles B project. The annular 40 marginal surfaces b, referred to above, are slightly raised and made perfectly flat on a plane at right angles to the axial plane of the field-ring and are of uniform width, except that they are provided with holes c. These 45 holes are located at equal distances apart, are intersected by the radial planes striking midway between the field-poles, and the outer segments of the mouths thereof are surrounded by semicircular embossments, the 50 faces of which are on the same plane as said marginal surfaces and form a part thereof.

Having described my invention, what I claim as new, and desire to secure by Letters Patent, is—

The design for a field ring or frame of an electric motor as herein shown and described.

In testimony whereof I have signed my name to this specification, in the presence of two subscribing witnesses, this 25th day of 60 November, 1899.

CHARLES A. LINDSTROM.
